George D. Avery
Letters Patent

This Specification referred to in those Letters Patent and making
part of the same containing a description in the words of the said George D. Avery
himself of his improvement in the Plough.

The kind part of the lower edge of the land side of the plough, to be furnished with a heel piece, or shoeing, in either of the following manners: - 1st. The heel piece for a two horse plough to be about 8 inches long and 1 $\frac{1}{2}$ inches square, with two holes crossing each other at a right angle through the middle. The heel piece is let into the lower edge of the land side, in its proper place, and is fastened with a screw bolt, which passes through the land side, or there may be 4 holes through the heel piece, 2 crossing each other at a right angle, near, and at equal distances from each end and fastened with 2 screw bolts passing through the land side. One object in putting on the heel piece, in this manner and form, and placing the holes and screw bolts as before described, is that it may work with either end foremost and with either side to the land, which will admit of 7 simple changes of its position, so as to have 8 different parts of it in succession to supply the working place at the heel. This heel piece may be adjusted at pleasure by putting leather (or something else) on its side next to the furrow, to set it to the land, or on its upper side to set it down, which will cause it, not only to work more uniformly, and to last much longer, but will regulate the pitch, and the taking of land and breadth of furrow of the plough. The holes through the land side may be round or long up and down like short mortises to admit the heel piece to be admitted or set down. 2nd. The heel piece to be made in the form of a parallelogram, or long square, about 8 inches long, 2 inches wide, and one inch thick, with a hole through the middle of its sides. This heel piece is let into the lower edge of the land side, in its proper place, and is fastened with a screw bolt which passes through the land side, or there may be two holes through this heel piece, near and at equal distances from each end, and fastened with two screw bolts passing through the land side. One object in putting on this heel piece, in this manner and form, and placing the holes and screw bolts as before mentioned

described, is that it may work with either end foremost, and with either side to the cane, which will admit of three simple changes of its position, so as to have four different parts of it in succession, to supply the wearing place at the heel, and this heel piece may also be adjusted in the manner before described. 3° The heel piece to be made in the form of two parallelograms, each to be about 8 inches long, 2 inches wide and 18 inches thick, which connected at their edges and forming two sides of a hollow square, an end view of which is thus with a hole through the middle of each side, this heel piece is let into the lower edge of the cane side, in its proper place, and is fastened with a screw bolt, which passes through the cane side, or there may be two holes through each side and at equal distances from each end and fastened with their screw bolts, or the outer edges may be thinner, an end view of which is thus One object in putting this heel piece on in this manner and form and placing the holes and screw bolts as before described, is, that it may work with either end foremost, and with either side to the cane, which will admit of one simple change of its position, so as to have two different parts of it in succession to supply the wearing place at the heel, and this heel piece may also be adjusted in the manner before described. 4° The heel piece to be made round, in the form of a cylinder, about 8 inches long, and 1½ inches diameter, this heel piece is let into the lower edge of the cane side in its proper place, and secured as mentioned below. And this heel piece may also be adjusted in the manner before described. These heel pieces may be made of cast iron, wrought iron, steel, or any kind of metal or wood, and may be lined with steel or iron, they may be made solid, or hollow, or hollow only at one or both ends, the corners may be left on, or taken off, the sides may be a little beveling for the greater convenience of casting in metal molts, or in bats they may be longer or shorter, and may be fastened on with screw bolts, with their ends made to fit into the hollows, or the cane side may be made with a little protuberance, or point, to fit into the hollow of one end of the heel piece, and the other end be fastened with a screw bolt made to fit it, and placed so as to draw the heel piece tight, or both ends of the heel pieces may be turned out at their corners, or a pin or knot may be put into one, or both ends, to which one end of a screw bolt may be fitted, to fasten it, the screw bolt may go through the cane side, at a right angle with its surface, or they may go through slants to

draw the heel piece tight at its ends, and there should be projections on the inner side of the long side with their surfaces so shaped that the heads of the screw bolts will rest on them evenly. Each and all the several modes of improving the plough, by heel pieces or shodding, as herein before specified, is claimed as my invention of improvement.
